UNITED STATES PATENT OFFICE.

JOSEPH APPELBAUM, OF NEW YORK, N. Y., ASSIGNOR TO TWIN BLADE CO. INC., OF NEW YORK, N. Y.

CLOTH-CUTTING KNIFE.

1,270,683.

Specification of Letters Patent. Patented June 25, 1918.

Application filed November 2, 1917. Serial No. 199,989.

To all whom it may concern:

Be it known that I, JOSEPH APPELBAUM, a citizen of the United States, and a resident of the city of New York, borough of Manhattan, in the county and State of New York, have invented a new and Improved Cloth-Cutting Knife, of which the following is a full, clear, and exact description.

Among the principal objects which the 10 present invention has in view are: to provide a knife for employment in conjunction with reciprocating machines of conventional type for cutting piled cloth; to provide a knife sharpened at opposite ends to augment the service period of said knife; and 15 to diminish the quantity of metal necessary to the manufacture of knives of the character mentioned.

Drawings.

Figure 1 is a side view of a knife blade constructed and arranged in accordance with the present invention;

Fig. 2 is an end view of the same;

Fig. 3 is a side view of a modified form 25 of the blade;

Fig. 4 is an end view of the same;

Fig. 5 is a further modified form of a blade constructed in accordance with the 30 present invention;

Fig. 6 is a cross section of the same, the section being taken as on the line 6-6 in Fig. 5;

Fig. 7 is a side view of a further modified 35 form of the invention;

Fig. 8 is a cross section thereof, the section being taken as on the line 8-8 in Fig. 7;

Fig. 9 is a side view of a fragment of the 40 head of a cloth-cutting machine showing the same as equipped with a knife constructed and arranged in accordance with the present invention.

Description.

Knives of the character herein disclosed 45 are employed for cutting cloth when piled or laid up on a cutting table. As shown in the drawings, in Fig. 9, the knife is held in a rocking arm 15, being secured in a guide head 16 between the cheeks of which the knife reciprocates. The head 16 has a base plate 17, which normally rests on the table partially under the cloth being cut.

50 Machines of the character indicated and

knives therefor have been used heretofore. The objection previously found has consisted largely in the fact that the wear on the knives which are necessarily thin, has been of a character to require the employment of 60 a large number of such knives and the loss of time necessary for sharpening the same.

While knives are provided with a sharp cutting edge along the front of the knife, the real cutting is performed by the short bottom end of the knife. Heretofore knives have been used having a holding shank and a cutting edge at the opposite extremes of the blade.

The present invention has in view as its 70 principal object, to reduce the number of knives needed and to economize in the time factor necessary to sharpening. Also to reduce, if possible, the labor expended in sharpening.

With the above-stated objects in view, the invention consists in providing cutting edges at opposite ends of each knife.

In Fig. 1, the cutting edges 18 are inclined upward from the point of junction with the front cutting or parting edge 19. From the points where the edges 18 are arrested to the back edge of the blade 20, the stock of the knife remains to form shanks 21. In the angle between the shanks 21 and the edges 18 of the blade, is placed the holding bolt 22, which secures the knife to the arm 15. The edges 18, 23 and 24 of certain of the forms of knives shown in the drawings, are slanted, the object being to permit the knives to give what may be termed a shearing cut, as they enter the pile of the cloth.

In Fig. 5 of the drawings, however, the knife shown has a straight edge 25. All of the knives have at the front edge thereof cutting edges, though, as above stated, it will be recognized that said edges do not function as cutting members.

In Fig. 7 of the drawings, the edges 24 100 form junctions with short cutting front edges 26. When using this form of blade, the said blade is completely reversed and the bolt 22 is inserted through the eyelets 27 provided therein. Though in some points this form of knife is desirable, an objection does exist in that it is necessary to remove certain of the fastening members to permit the thread of the bolt 22 through said eyelets 27, whereas in the other forms of the 105 110

knives, said bolt is slipped edgewise into the recess between the cutting edge 18 and the shanks 21, or into the edge-opening slots of the form of knife shown in Fig. 3, and 5 in the angle 29 between the shank 21 of the knife shown in Fig. 5 and the straight edge 25 adjacent.

In all of the knives, however, it will be found that cutting edges are provided at 10 both ends of the knife, in such manner that as one end becomes dull, the knife may be inverted in its operating position and present to the work being performed a fresh cutting member.

Also it is obvious that when the knife is 15 sharpened, both ends being sharpened at the same time, the labor in this operation is curtailed or much reduced.

Claim.

20 A knife as characterized having the opposite ends thereof provided each with an end cutting edge and a recess for receiving a fastening bolt adjacent said end cutting edge, the longitudinal edges of said knife 25 being sharpened for separating the cloth in advance of the cutting edges of said knife.

JOSEPH APPELBAUM.
